7 Claims. (Cl. 29—155.5)

This invention relates to a method of making a series connected thermopile by coating dissimilar metals on a strand of insulating material.

An object of the invention is to provide an improved process for making thermopiles having a large number of thermoelectric junctions and having increased sensitivity.

According to the invention, a glass fiber strand, or a strand of other dielectric material, is wound around a mandrel in a generally helical pattern with each turn of the windings spaced from adjacent turns. While supported on the mandrel one-half of the length of each turn is coated with a metal by dipping, spraying or the like, and subsequently, the remaining half of the length of each turn is coated with a second and dissimilar metal. The second metal overlaps the first metal to provide a series of spaced thermoelectric junctions extending throughout the length of the helically wound strand.

The metal coated strand is then removed from the mandrel and connected in an electrical circuit to provide a multi-junction thermopile.

The present invention provides a simple and inexpensive method of producing a series-connected thermopile having a large number of junctions. As the metal coating on the strand is relatively thin, the heat loss from the junction by conduction through the metal will be decreased and this results in a greater heat differential between the hot and cold junction and a more efficient thermopile.

In addition the nominal resistance of the thermopile is high and therefore the output signal may be detected by a circuit having a high input impedance, such as a conventional electronic amplifier.

The drawings illustrate the best method presently contemplated of carrying out the invention.

In the drawings:

Figure 1 is a perspective view of the mandrel with the glass fiber wound thereon;

Fig. 2 is a schematic view of a portion of the length of the turns of the fiber being coated with a metal;

Fig. 3 is a view similar to Fig. 2 showing the remaining portion of the length of each turn being coated with a second and dissimilar metal;

Fig. 4 is a perspective view of the thermopile of the invention as removed from the mandrel;

Fig. 5 is a perspective view of the compressed helix and having an insulating coating thereon; and

Fig. 6 is an enlarged section showing metal coating.

In constructing the thermopile of the present invention, a glass fiber strand 1, or a strand of a suitable dielectric material, is wound around a generally cylindrical mandrel 2 in a spiral pattern to form a helix. Each turn or convolution of the helix is spaced from adjacent turns to provide a substantial gap therebetween.

The outer surface of mandrel 2 is provided with a series of longitudinal extending serrations 3 and the strand 1 is supported on the outer edge of the serrations 3 to provide a series of line contacts between the strand 1 and the mandrel 2, as best shown in Figs. 2 and 3.

To provide a plurality of thermoelectric junctions

throughout the length of the strand 1, the mandrel and the helix are dipped into a bath of a molten metal or alloy 4 contained within a trough 5 or the like. As shown in Fig. 2, the mandrel is dipped into the metal 4 such that approximately the lower longitudinal half of the mandrel is immersed in the metal, thereby coating about one-half of the length of each of the turns of strand 1 with the metal. The serrations 3 permit the metal 4 to flow behind the strand and coat the greater portion of the inner surface of the strand, with the exception of the portions contacting the edges of serrations 3.

The metal or alloy 4 employed in the bath may be any metal having a melting point lower than the transition temperature of strand 1 so that the strand will not deform or be decomposed by the heat of the metal. With the use of a glass strand, metals such as lead, tin, bismuth and zinc can be employed.

After approximately one-half of the length of each turn of strand 1 is coated, the mandrel is removed from the bath and the metal coating 6 is allowed to solidify. The mandrel is then placed in a second trough 7 containing a metal 8 dissimilar from metal 4. Under this step of the invention the uncoated half of the mandrel is dipped in the metal 8 so that the uncoated portion of each turn of the strand 1 is coated with metal and the metal coating 9 overlaps the end portions of the coating 6 on each turn to provide a series of thermoelectric junctions 10 which are disposed in spaced relation throughout the length of the strand. The helix is, in effect, a series of sections of the metal coating 6 alternating and electrically connected to a series of sections of the metal coating 9 and extending substantially the length of the helix.

The mandrel is then removed from the trough 7, and the coated strand withdrawn from the mandrel. The terminals or ends of the metal coated strand are then connected by leads 11 in an electric circuit, as shown in Fig. 4, to provide a simple and efficient thermopile unit. The element 12 shown in Fig. 4 is a diagrammatic representation of an electrical device such as a relay winding, a detection apparatus or a source of power of the thermopile is operated to develop a differential in temperature.

The electromotive force of the thermopile can be varied by varying the number of thermoelectric junctions, by changing the metals used, or by coupling with other thermopiles.

While the above description is directed to coating the strand 1 by dipping in a metal bath, it is contemplated that the strand may be coated with metal by other processes such as spraying, sputtering or vacuum plating. In these methods of coating, it may be necessary to mask the portion of the strand not to be coated in order to obtain the separate and alternate coatings 6 and 9 of dissimilar metals. By using spraying, sputtering or vacuum plating higher melting metals such as constantan, copper, iron, chromel and alumel can be employed as the metal coatings 6 and 9.

It is also within the scope of the invention to employ a smooth surfaced mandrel 2 instead of the serrated mandrel. With the use of a smooth mandrel, the inner surface of the strand 1 would be uncoated, but the electromotive force developed by the thermopile can be maintained by increasing the thickness of the coating on the outer surface of the strand.

The thermopile of the invention can be used in the helical form in which it is removed from the mandrel, or it can be bent into a single straight thermopile unit if the ductility of the metal permits bending, or it can be compressed in helical form into a dense compact unit as shown in Fig. 6. If compressed in helical form, the coating sections 6 and 9 are insulated from each other by applying a layer 13 of rubber, plastic or wax or the like to the thermopile. In this situation the thermoelectric

junctions 10 are preferably masked to prevent the junctions from being coated with the insulating material.

As a glass fiber strand can be made with a very small diameter or cross-sectional area and considerably smaller than metal wire can be made under normal procedures, the cross-sectional area of the thermopile will be correspondingly small. This enables a larger number of junctions 10 to be concentrated in a given area and in effect increases the electromotive force developed by the thermopile.

Various modes of carrying out the invention are contemplated as being within the scope of the following claims particularly pointing out and distinctly claiming the subject matter which is regarded as the invention.

I claim:

1. A method of making a thermopile, comprising winding a strand of insulating material around a mandrel in the form of a helix, spacing each turn of the helix from adjacent turns to provide a gap therebetween, coating a portion of the length of each turn with a metallic material, coating the remaining portion of the length of each turn with a second metallic material different from said first metallic material and in overlapping relation with a portion thereof so that a thermocouple junction is formed on each turn, removing the helix from the mandrel, and connecting the terminals of the helix in an electrical circuit to provide a series connected thermopile therein.

2. A method of making a thermopile, comprising winding a strand of insulating material around a mandrel having a series of generally longitudinal ridges extending around the periphery thereof to form a helix, coating substantially one-half of the length of each turn with a metal, coating the remaining half of each turn with a second metal having different thermoelectric properties than said first metal and lapping said second metal over the ends of said first metal coating on each turn to provide a thermocouple junction on each turn, removing the helix from the mandrel, and connecting the terminals of the helix in an electrical circuit to provide a series connected thermopile therein.

3. A method of making a thermopile, comprising winding a strand of dielectric material around a mandrel in the form of a helix, spacing each turn of the helix from adjacent turns to provide a gap therebetween, coating a portion of the length of each turn with a metallic material, coating the remaining portion of the length of each turn with a second metallic material different from said first metallic material and lapping the second metallic material over the ends of the first metallic material on each turn to provide a thermocouple junction on each turn, removing the helix from the mandrel, coating the metal covered helix with a flexible insulating material while masking the electrical junctions to prevent said insulating material from coating said junctions, compressing the helix lengthwise to bring the turns into substantially contiguous relation, and connecting the ends of the helix in an electrical circuit to provide a series connected thermopile therein.

4. A method of making a thermopile, comprising winding strands of glass fiber in the form of a helix, spacing each turn of the helix from adjacent turns to provide a

gap therebetween, supporting each turn of the helix on the mandrel at a series of spaced locations on said turn, dipping the helix in a bath of a molten metallic material to coat a portion of the length of each turn with said material, removing the helix from the bath and solidifying said metallic material, dipping the helix in a bath of a second molten metallic material having different thermoelectric properties than the first named metallic material to coat the remaining portion of the length of each turn with said second metallic material and lapping said second metallic material over the ends of the first metallic material on each turn to provide a thermocouple junction on each turn, and connecting the ends of the helix in an electrical circuit to provide a series connected thermopile therein.

5. A method of making a thermopile, comprising winding a strand of dielectric material around a mandrel having a series of generally longitudinally extending ridges spaced around the periphery thereof to form a helix, dipping the helix into a molten metal in a direction transverse to the axis of the helix to coat a portion of the length of each turn of the helix with said metal, dipping the helix into a second bath of molten metal to a sufficient depth to overlap the ends of the first metallic coating and provide a thermocouple junction on each turn, and connecting the ends of the helix in an electrical circuit to provide a series connected thermopile therein.

6. A method of making a thermopile, comprising winding a strand of dielectric material around a mandrel having a series of generally longitudinally extending ridges spaced around the periphery thereof to form a helix, dipping the helix into a molten metallic material in a direction transverse to the axis of the helix to coat a portion of the length of each turn of the helix with said metallic material, dipping the helix into a second bath of molten metallic material to a sufficient depth to overlap the ends of the first metallic coating and provide a thermocouple junction on each turn, coating each individual turn of the metallic covered helix with a flexible insulating material while maintaining the electrical junctions between said first and second metallic material free of said insulating material, compressing the helix lengthwise to bring the turns into substantially contiguous relation, and connecting the ends of the helix in an electrical circuit to provide a series connected thermopile therein.

7. A method of making a thermopile, comprising winding a strand of glass fibers in a generally helical pattern with each turn of the helix being spaced from adjacent turns, coating a portion of the length of each turn with a first metal, coating a second portion of the length of each turn with a second metal different from said first metal and in overlapping relation with the ends of the first metal on each turn to provide a thermocouple junction on each turn, and connecting the ends of the helix in an electrical circuit to provide a series connected thermopile therein.
